UNITED STATES PATENT OFFICE

EDWARD MARTIN HAWKINS, OF GLEZEN, INDIANA, ASSIGNOR OF ONE-HALF TO
WARREN E. POUDER, OF PIKE COUNTY, INDIANA

TRANSFER MEANS FOR MINE CARS

Application filed June 21, 1930. Serial No. 462,906.

The transfer of empty mine cars, for instance, coal cars, from the empty track to the loading track where the loaded car will be taken away by an electric engine, requires special means which constitutes the occasion for the present invention.

The object of the invention is to provide a simple, efficient, portable, and foldable transfer means for the foregoing purpose, embodying improvements enabling the device to be applied to any point of the parallel empty and loading tracks, and by which the empty car can be run onto the present transfer means and quickly shifted to the loading track.

The invention also comprises special means to transfer the cars, prevent them from getting beyond control, and to enable the device to be swung out of the way when it is necessary to clear either the empty track or the loading track for the passage of the electric engine, or for other causes.

The present improved transfer means also is adapted for folding into a reasonably compact form for transportation from point to point where necessity arises for its use.

With this, and other objects hereinafter appearing, the present transfer means embodies those features of construction and combinations of parts with associated functions hereinafter described and shown in the accompanying drawings, in which:

Figure 1, is a plan view showing the transfer means applied to the empty and loading tracks;

Fig. 2, is an end elevation showing the coal car on the transfer car immediately after it has been elevated;

Fig. 3, is a side elevation, dotted lines showing the coal car en route to the loading track, full lines showing the transfer and coal cars above the loading track, a section of the transfer track being raised to clear the "empty" track; and

Fig. 4, is a side elevation of the transfer means folded up, ready for transportation.

In practice, the tracks 1 and 2 are parallel and separated from each other a distance which may vary from five to twenty-five feet. Either one of the tracks may be used for the

empty cars and hence it may be styled the "empty" track and the remaining track used for the loading of the cars, being more conveniently located to the supply of the material, for instance, coal. The electric engine 55 which moves the empty or loaded cars, may travel on either track 1 or track 2. With such an arrangement, the necessity arises for the transfer of empty cars from one track to the other and, in order to save overhead charges, 60 it is of importance that the transfer be quickly consummated and that the transfer means be located at the point where it is needed. Ordinary turn tables and cross tracks not successfully meeting the necessities of a situation of this character, I have devised the present invention for the purpose of effecting quick and easy transfer at any point of the two tracks, such means being now described. 65

The present means is unitary, avoiding the accidental loss of necessary parts. There is a center section comprising rails 3 supported by ties 4, and foldable end sections comprising rails 5 which are jointed or hinged at 6 to the rails 3 and form a continuation thereof. The ends of the rails 5 are provided with upstanding abutments 7 to prevent the transfer car 8 which runs on the rails 3 and 5, from running off the ends of the rails 5. 70 75

The rails 5 are mounted on stringers 9 which are arranged in crosswise relation thereto and adapted to rest on the ties of the tracks 1 and 2.

Inclined rails 10 are carried by cross pieces 85 or ties 11 so that the inclined rails overlie the rails of the tracks 1 and 2, enabling the wheels of the mine or coal car 12 to run up above the rails of the empty track and onto the transfer car 8 and to be run down from 90 the transfer car onto the rails of the loading track, or vice versa. The ties or cross pieces 11 have depending end parts 13 which lie outside the rails of the respective tracks 1 and 2 and prevent lateral displacement of 95 the device, thus keeping the inclined rails 10 in alignment with the rails of said tracks 1 and 2.

The transfer car 8 being adapted to travel on the rails 3, 5, can be alined with the rails 100

of the tracks 1 and 2 so that the car 12 may be received onto the transfer car 8 or allowed to pass therefrom. To line up the transfer car 8 with the inclined track sections of rails 5 10 and also to hold the car 12 on the car 8, the car 8 is provided with channels 14 which receive the flanges of the wheels of the car 12.

If it becomes necessary to clear either track, the rails 5 can be swung upwardly, as shown 10 in Fig. 3 to allow the cars or engine to pass.

The transfer means may be readily folded into compact form, as shown in Fig. 4 so that it may be shifted from place to place and positioned at any desired point of the 15 tracks 1 and 2. When thus positioned, the rails 3, 5 are opened out, the ties 4 are loaded on the road bed between the tracks 1 and 2, and the rails 5 are opened out horizontally to bring the inclined rails 10 in alinement 20 with the rails of the respective tracks and they are kept in that position by the retaining devices 13.

What I claim is:

1. Means for transferring cars from one 25 track to another track, comprising cross rails extending from one track to the other track, pairs of inclined rails connected to the aforesaid cross rails at both ends of the latter, and a transfer car adapted to travel on the cross 30 rails, whereby a car may be run up to the transfer car or run down from said transfer car onto either track without necessitating re-laying or shifting of the cross rails, said cross rails and inclined rails being connected 35 together.

2. Means for transferring cars from one track to another track, comprising cross rails extending from one track to the other track, inclined rails connected to the aforesaid rails, 40 and a transfer car adapted to travel on the cross rails, whereby a car may be run up to the transfer car or run down from said transfer car onto either track, said inclined rails and cross rails being joined together so that 45 the cross rails and inclined rails may be folded for transportation or either set of inclined rails may be swung from the track to permit the passage of a car or engine thereon.

50 3. A unitary transfer means whereby cars may be shifted laterally from one track to another, comprising a cross track having a center section adapted to rest upon the road bed between the aforesaid tracks, end sections jointed to the center section in foldable relationship thereto, stringers, connected to the end sections and adapted to rest on the ties of the respective tracks, cross pieces carried by said stringers, inclined rails carried 55 by said cross pieces and adapted to be placed in overlying relationship to the rails of the respective tracks, means for holding the stringers in position and the inclined rails alined with the rails of the respective tracks, 60 and end abutments for the cross track, said 65

cross track being adapted to support a transfer car, and said inclined rails permitting a car to be run up onto the transfer car or down from the transfer car.

In testimony whereof I affix my signature. 70
